UNITED STATES PATENT OFFICE.

WILLIAM J. O'CONNOR, PATRICK WALSH, AND EDWARD L. MARTIN, OF KANSAS CITY, MISSOURI.

BEER-STILL.

SPECIFICATION forming part of Letters Patent No. 328,708, dated October 20, 1885.

Application filed August 1, 1885. Serial No. 173,251. (No model.)

To all whom it may concern:

Be it known that we, WILLIAM J. O'CONNOR, PATRICK WALSH, and E. L. MARTIN, citizens of the United States, residing at Kansas City, 5 in the county of Jackson and State of Missouri, have invented certain new and useful Improvements in Beer-Stills; and we do hereby declare the following to be a full, clear, and exact description of the invention, such as 10 will enable others skilled in the art to which it appertains to make and use the same.

Our invention relates to an improvement in beer-stills; and it consists in the improved construction and combinations of parts hereinabove fully described, and pointed out in the 15 claims.

In the drawings, Figure 1 is a longitudinal vertical section of our improvement. Fig. 2 is a horizontal section on the line *x x* of Fig. 20 1, and Fig. 3 is a horizontal section on the line *y y* of Fig. 1.

In the accompanying drawings, in which like letters of reference indicate corresponding parts in all the figures, A represents the still proper; B, the heater and condenser, and C the worm or final condenser. The still A consists of a cylinder, B', which is divided into a series of horizontal compartments or chambers, D, by means of partitions E. These partitions E are each provided with a series of pipes, G, which are covered by caps *a*, whereby communication is established between the several compartments. The upper two partitions of the series E have openings *b*, which 35 are controlled by valves *c*. A space or compartment, *e*, is left between the lower partition and the series F, and communicating with said space or compartment is a pipe, *f*, by means of which steam may be introduced to 40 the said space or compartment to heat the mash within the still. Communicating with the space or compartment *e* is a device, H, for blowing out the mash from the said space after the spirits have been extracted from the 45 said mash.

Connecting the several compartments of the still formed by the partitions F are a series of pipes, H H', the pipes H being located at about the centers of the partitions, while the 50 pipes H' are located at the sides of the same.

By this arrangement one compartment is connected with the one above it at the center, and this said last-mentioned compartment is connected with the adjacent compartment at one side. Surrounding the lower ends of the pipes 55 H H' are pans or basins I, the purpose of which is to prevent the steam passing through the still from interfering with the mash as it drops from one compartment to the subjacent or compartment below. Upon the upper side 60 of each of the partitions F are spirally-arranged partitions I, thus forming spirally-arranged ways or passages *h*, through which the beer or mash passes. The pipes H communicate with said ways or passages at the sides of 65 the same, so that before the beer or mash can escape to the lower compartment it must pass through these spirally-arranged ways or passages, so that it is thoroughly vaporized by the time the lower compartment is reached. 70 The heater or condenser B is arranged on a plane above the still A, and said heater or condenser consists of a cylinder, within which is a spirally-arranged pipe, J. The said pipe J passes out through the side of the cylinder 75 and communicates with the still A in the third compartment from the top of said still. By this means it will be seen that the beer or mash placed in the pipe J will be carried through said pipe into the still A, and from 80 the compartment which it enters to the several compartments below.

K represents a pipe which connects the lower end of the heater or condenser B with the upper compartment in the still A, the 85 purpose of which pipe will be more fully set forth.

L represents a pipe which communicates with the still A at the upper end of the same and at or about the center thereof, said pipe 90 entering the condenser or heater B at the lower end thereof. The purpose of this pipe is to carry the vapor from the still A to the condenser B. Within the condenser B, at suitable intervals, are placed dividing-plates M, 95 which are narrower than the casing, thus leaving a space between their edges and the sides of the casing.

N represents pipes which communicate with the condenser B at the points at which the di- 100

vision-plates are located, the lower ends of said pipes extending to the bottom of the condenser and there entering the same. The worm or final condenser C is placed at some little distance from the heater or condenser B, and consists of a cylinder, into which extends a pipe, O, the pipe O communicating with the upper end of the condenser or heater B, and being coiled within the cylinder of the condenser, 10 the end of said pipe extending through said cylinder.

The operation is as follows: The beer or mash is placed in the pipe J, and from there passes into the third compartment of the still 15 A. Steam is admitted through the pipe in the lower end of the still. The vapor caused by the mash becoming heated passes up through pipe L into the heater or condenser, and there serves to thoroughly and effectually 20 heat the mash within the pipe J. The vapor coming in contact with the cool pipes through which the mash is conveyed is in part cooled and a portion drops to the bottom of the heater or condenser, and from there it passes 25 through the pipe K to the still, where it is boiled. The vapor which may arise beyond the dividing-plates and there become cooled is carried back to the bottom of the condenser by the pipes N, and then back into the still. 30 The vapor which is not cooled or which passes through the heater is carried by the pipe O in the final condenser, and there condensed by a cooling agent placed in the cylinder of the condenser and surrounding the part of the 35 pipe O which is coiled.

In the upper end of the condenser or heater B we have shown a plate, P, the purpose of which is to prevent heavy matter from being blown through the heater into the final condenser. 40

Having thus described our invention, we claim—

1. The combination, with a still, of a heater having a coiled pipe therein, said pipe communicating with the still, the division-plates 45 M, the pipes N, arranged as described, the plate P, the pipes K L, the final condenser, and the pipe connecting the final condenser and the heater, substantially as set forth.

2. The combination, with the still divided 50 into a series of compartments or chambers, of the vapor-pipes, pipes connecting the compartments, the spirally-arranged partition-walls, the heater having the coiled pipe J, communicating with the still, the pipes K L, 55 the plate M, pipes N, and final condenser, substantially as set forth.

3. In a beer-still, a heater having a coiled pipe therein, plates M, the pipes N, extending from the plates M and communicating with 60 the heater below the coiled pipe, and the plate P, substantially as set forth.

In testimony whereof we affix our signatures in presence of two witnesses.

W. J. O'CONNOR.
PATRICK WALSH.
EDWARD L. MARTIN.
